CLAIM

The ornamental design for a tray for a salon chair, as shown and described.

DESCRIPTION

FIG. 1 is a perspective view of a tray for a salon chair showing our new design;

FIG. 2 is a front elevational view thereof;

FIG. 3 is a side elevational view thereof;

FIG. 4 is a rear elevational view thereof;

FIG. 5 is a top plan view thereof; and,

FIG. 6 is a bottom plan view thereof.

The broken lines showing a portion of a chair are for the purpose of illustrating unclaimed environmental structure only.
